United States Patent Office

Des. 230,608
Patented Mar. 5, 1974

230,608

ELECTRONIC COMMUNICATIONS APPARATUS

J. Pratt Winston, 305 S. Dillard St.,
Durham, N.C. 27702

Filed Nov. 20, 1972, Ser. No. 307,871

Term of patent 14 years

Int. Cl. D14—03
U.S. Cl. D26—14 B

FIG. 1

FIG. 2

FIG. 3

FIG. 4

FIG. 5

FIG. 6

FIG. 7

FIG. 8

FIG. 9

FIG. 10

FIG. 1 is a plan view of the electronic communications apparatus showing my new design.

FIG. 2 is a view in elevation of the design shown in FIG. 1.

FIG. 3 is a bottom view of the design shown in FIG. 1.

FIG. 4 is a view in elevation of a modified form of the invention shown in FIG. 1.

FIG. 5 is a bottom view of the design shown in FIG. 4.

FIG. 6 is a side elevation of a further modified form of the invention.

FIG. 7 is a plan view of the design shown in FIG. 6.

FIG. 8 is a front elevation of the invention shown in FIG. 6.

FIG. 9 is a bottom view of the design shown in FIG. 6, and

FIG. 10 is a rear elevation of the design shown in FIG. 6.

I claim:

The ornamental design for an electronic communications apparatus, as shown and described.
